CLAIM

The ornamental design for a reel seat for use on fishing rod, as shown and described.

DESCRIPTION

FIG. 1 is a perspective view of a reel seat for use on fishing rod embodying my new design;

FIG. 2 is a front view thereof, the rear view being a mirror image thereof;

FIG. 3 is a top plan view thereof;

FIG. 4 is a bottom view thereof;

FIG. 5 is a left side view thereof;

FIG. 6 is a right side view thereof;

FIG. 7 is a sectional view thereof taken along the line 7—7 of FIG. 3;

FIG. 8 is a referential view showing use state thereof. The broken line showing of part of a fishing rod is for illustrative

purposes only and form no part of claimed design; and,

FIG. 9 is another referential view showing use state thereof. The broken line showing of part of a fishing rod is for illustrative purposes only and form no part of claimed design.
